UNITED STATES PATENT OFFICE.

JOSEPH HAMPSON AND SAMUEL SIMON, OF MANCHESTER, ENGLAND.

METHOD AND APPARATUS FOR DESIGNING STRIPED EFFECTS.

Application filed October 9, 1924. Serial No. 742,676.

To all whom it may concern:

Be it known that we, JOSEPH HAMPSON and SAMUEL SIMON, both British subjects, residing at Manchester, county of Lancaster, 5 England, have invented certain new and useful Improvements in Methods and Apparatus for Designing Striped Effects, of which the following is a specification.

This invention relates to the designing of 10 coloured stripe effects for textile fabrics made from cotton, silk, wool, linen, jute, cellulose or other textile fibres.

It comprises the use of a plurality of 15 cards, some white and the others coloured in various colours, on one or more edges which when assembled or grouped together will present a variety of striped designs or effects either in single colours or in two or more colours according to the position in 20 which the cards are grouped.

Textile manufacturers, designers, buyers, salesmen and others may create their own 25 designs by grouping and regrouping the various white and coloured cards until the desired stripe effect is produced.

The invention will be fully described with reference to the accompanying drawings.

Fig. 1. is a perspective view of a single card.

Fig. 2. is a perspective view of a group of cards.

Fig. 3. is a perspective view of a group of cards coloured on a plurality of edges.

Fig. 4. is a perspective view of cards assembled in a holder where they can be grouped and re-grouped until a desired 35 striped effect is produced.

Fig. 5. is a perspective view of cards grouped and arranged together and 40 clamped in a case or holder.

Fig. 6. is a perspective view of a holder for several groups of cards separated by removable partitions.

In carrying out the invention we provide 45 a plurality of cards A some of which are white and others coloured along one edge a or along two or more edges a^1 a^2 . Any number of colours may be selected and any number of cards may be coloured one of 50 such colours. The edges a^1 and a^2 may be plain or may be the same colour as the edge a or all three or four edges may be of different colours so that in one card there may be two, three or four distinct colours and when 55 grouped together two, three or four differ-

ent designs or stripe effects are produced. The edge a may be of a single colour or two or more colours may be on the edge a to produce fancy woven effects such as are known as double-stitch, jacquard or printed yarn 60 effects. The flat sides or faces a^3 of the cards may be either white or coloured as found most convenient for sorting them.

The cards A may be made of card, cardboard, wood, metal or other suitably stiff 65 material and the edges painted or enamelled in the various colours and the cards A may be of various thicknesses, some thicker than others to facilitate making broad stripes.

The cards are grouped together either on 70 an open holder B as shown in Fig. 4 or placed in cases C as in Figs. 5 and 6 in juxtaposition, the different colours on their edges forming the stripe design.

Any portion of a design can be modified, 75 reduced or enlarged by the addition or subtraction of one or more cards and any design created can be readily and quickly changed by adding to or reducing the number of cards or by removing the cards 80 and replacing them by cards of another shade or colour.

In the construction shown in Fig. 5 the holder B is provided with a thumb screw b by which the cards A are pressed tightly together to give to the edge surface a of the cards an even appearance marked with coloured stripes.

In application to produce a design one or a plurality of say twenty white edged cards 90 are placed in the holder B or C one, or a plurality of coloured edged cards say blue placed adjacent to them, one or a plurality of coloured edged cards say red, then one or more white edged cards, and so on until 95 a design in any desired colour or widths of stripes is obtained. For a repeat the case C Fig. 6 may be employed, the pattern being repeated in each group represented therein.

The card design created can next be applied to the material it has to be reproduced in, taking as many white or coloured threads as may be required to equal the corresponding number of cards used.

What we claim as our invention and desire to protect by Letters Patent is:—

1. The method or process of designing striped effects and patterns for reproduction on textile fabrics which consists in grouping and assembling together side by side in 110

relation to one another a plurality of cards the edges of which are white and coloured respectively.

2. Apparatus for designing striped effects and patterns for reproduction on textile fabrics comprising a plurality of cards grouped together some provided with white edges and others with coloured edges in a variety of colours.
- 10 3. A card for producing striped effects and patterns as in claim 2 coloured along one edge.
4. A card for producing striped effects and patterns as in claim 2 coloured along 15 two edges.
5. A card for producing striped effects and patterns as in claim 2 coloured along three edges.
6. A card for producing striped effects and patterns as in claim 2 coloured along 20 four edges.
7. Apparatus for designing striped effects and patterns for reproduction on textile fabrics comprising the combination of a

plurality of cards provided with white 25 edges, a plurality of cards provided with coloured edges in various colours and a holder in which to group and assemble the cards in the desired order to produce the effect required.

- 30 8. Apparatus for designing striped effects and patterns for reproduction on textile fabrics comprising the combination of a plurality of cards provided with white edges, a plurality of cards provided with 35 coloured edges in various colours and a holder in which to group and assemble the cards in the desired order to produce the effect required and a thumb screw to press the cards together.

40 In testimony whereof we have hereunto set our hands in presence of two subscribing witnesses.

JOSEPH HAMPSON
SAMUEL SIMON.
